UNITED STATES PATENT OFFICE.

LOUIS N. D. WILLIAMS, OF OGONTZ, PENNSYLVANIA.

KNITTING-MACHINE

1,163,296.

Specification of Letters Patent.

Patented Dec. 7, 1915.

Application filed February 13, 1914. Serial No. 818,465.

To all whom it may concern:

Be it known that I, LOUIS N. D. WILLIAMS, a citizen of the United States, residing in Ogontz, Pennsylvania, have invented certain Improvements in Knitting Machines, of which the following is a specification.

The object of my invention is to combine with a knitting machine latch needle means for preventing injury to said latch by contact with an unyielding obstacle lying in its path on the retracting movement of the needle, or when the projecting movement thereof begins, and means for insuring the engagement of the knitting yarn by the needle hook and preventing the drop stitches which result when the latch closes the hook of the needle at the time when the yarn is being fed thereto. This object I attain in the manner hereinafter set forth, reference being had to the accompanying drawings, in which—

Figure 1 is a view, partly in side elevation and partly in section and on an enlarged scale, of a knitting machine latch needle showing, in full lines, the latch in its fully opened position, but illustrating in combination with the needle a jack at the front of the needle for lifting the latch, as indicated by dotted lines; Fig. 2 is a similar view but illustrating in full lines the latch in the closed position and the jack in position to coöperate with the latch to open the same, as indicated by dotted lines; Figs. 3 and 4 are views similar to Figs. 1 and 2 but illustrating a construction of latch and jack in which the jack is at the back of the needle; Fig. 5 is a sectional view of a needle with a modified form of rear jack; Fig. 6 is a view, partly in side elevation and partly in section, showing a modified type of latch opener; and Fig. 7 is a horizontal section of the same.

In the drawings, 1 represents the stem or shank of a knitting machine needle, 2 the hook at the upper end of the same, 3 the swinging latch, and 4 the slot in the needle stem for the reception of said latch.

In knitting machines of the finer gages, in which very fine latch needles are used, the latch, when fully opened, occupies a position so nearly parallel to the line of movement of the needle that if its end contacts with an unyielding obstacle during the retraction of the needle the pressure upon the latch is resisted by the pivot pin 5 and

the latch will not swing on this pivot but will be distorted or broken by the pressure upon it. With the view of overcoming this objection I provide for swinging the latch outwardly from its fully opened position to such an extent that when, on the retraction of the needle carrying the latch the point of the latter comes into contact with an unyielding obstacle, the pressure upon the latch will cause it to swing upon its pivot and prevent injury to the latch. One means for accomplishing this object is a jack 6 mounted in front of the needle and controlled by cam mechanism independent of that which controls the needle, whereby the jack can be caused to have longitudinal movement independent of that of the needle, and, when the needle reaches such a position in its retracting movement that it becomes desirable to raise the latch from its open position, shown by full lines in Fig. 1, the jack 6 may be caused to move independently of the needle and act upon the back of the latch to lift the same to the position shown by dotted lines, and may be retained in this projected position until the retracting movement of the needle has been completed. It is also desirable to prevent the closing of the hook by the latch at the time that the thread is being fed to the needle, otherwise the closed latch will prevent the thread from entering the hook of the needle and will cause a drop stitch. To effect this result the butt of the latch has a cam face 7 and the forward end of the jack 6 has a cam face 8 which, when the jack is moved longitudinally upon the needle to the proper position, engages with the cam face 7 and causes the closed jack (shown by full lines in Fig. 2) to be swung outward to the position shown by dotted lines in said figure, thus opening the hook and permitting engagement of the knitting yarn therewith.

In the needle shown in Figs. 3 and 4 the jack 6 is disposed at the back of the needle instead of at the front of the same, and the latch is provided with a heel 10 at the butt, the back of the latch being acted upon by the forward end of the jack 6 so as to lift the latch from the fully opened position shown by full lines in Fig. 3 to the position shown by dotted lines in said figure, said jack 6 being also adapted to act upon the heel 10 to move the latch from the closed position shown by full lines in Fig. 4 to the partially opened position shown by dotted lines in Fig. 5.

ted lines in said figure, or to the fully open position, if desired, depending upon the extent of movement of the jack independently of the needle.

5. When the jack is at the back of the needle said jack may have an operating butt passing through a slot in the needle stem, as shown for instance in connection with the jack 6 in Fig. 5, or instead of using a reciprocating jack moving independently of the needle a fixed bit such as shown at 13 in Figs. 6 and 7 may be employed, this bit engaging with the heel of the latch as the needle is retracted and serving to open the latch for the entrance of the yarn into the hook of the needle.

I claim:

1. The combination, in a knitting machine, of a latch needle having a pivoted latch and a device acting upon the butt of the latch to swing the spoon of the latch outwardly from its fully closed position, said latch and latch opener being susceptible of movement one in respect to the other in the direction of travel of the needle.

2. The combination of a knitting machine needle having a pivoted latch with a jack movable longitudinally independently of the needle and so disposed as to act upon the back of the latch to swing the spoon of the

same outwardly when the latch is open and upon the butt of the latch to swing the spoon of the same outwardly when the latch is closed.

3. The combination of a knitting machine 35 latch needle having a pivoted latch, with a jack mounted upon said needle but movable longitudinally independently thereof, to act upon the latch so as to swing the same outwardly from its fully open position. 40

4. The combination of a knitting machine latch needle having a pivoted latch, with a jack mounted upon said needle but movable longitudinally independently thereof, to act upon the latch to move the same outwardly from its closed position. 45

5. The combination of a knitting machine latch needle having a pivoted latch, with a jack mounted upon but movable independently of the needle and acting upon the 50 latch so as to either raise the same from its open position or swing it outward from its closed position.

In testimony whereof, I have signed my name to this specification, in the presence of 55 two subscribing witnesses.

LOUIS N. D. WILLIAMS.
